UNITED STATES

FREDERICK W. RICHARDS, OF NORTH ATTLEBOROUGH, MASS.
ASSIGNOR TO HENRY H. CURTIS, OF SAME PLACE.

BUTTON OR STUD.

SPECIFICATION forming part of Letters Patent No. 358,882, dated March 8, 1887.
Application filed January 6, 1887. Serial No. 223,545. (No model.)

To all whom it may concern:

Be it known that I, FREDERICK W. RICHARDS, of North Attleborough, county of Bristol, and State of Massachusetts, have invented a new and useful Improvement in Buttons and Studs; and I do hereby declare the following specification, taken in connection with the accompanying drawings, forming a part of the same, to be a description of the invention. This invention relates to that variety of buttons having two L-shaped arms, one secured rigidly to the button, one being adapted to be rotated or turned to facilitate the application to a garment, and

in any preferred manner, to pass into the notches *d*' on the plate *D*, as shown in Fig. 4, to lock the plate and thereby the shoe portion *c* in position. The shank *b* of the arm *B* passes through the tubular shank *b*' of the arm *C*, as shown in Fig. 5, and shank *c*' of the arm *E*, which portion *e* forms a bridge over the plate *D*, as shown in Figs. 4 and 5, the arm *C*, with its attached plate *D*, being capable of rotating upon the shank *b*'.

To apply the button, the shoe portion *c* is turned half a revolution to overlie the shoe portion *b*, as shown by dotted lines in Fig. 1, and by full lines in Fig. 5, the spring *F*, *b* the engagement of its ends with the notches in the plate *D*, locking the shoe parts in such holes, so that the flange *b* occupies said hole a

half a

which is
the L-shaped
arm C, and the spr
and engaging said
arms in position, su
FREDERIC
secured to the head
disk to lock the
as set forth.
CHARDS.
